UNITED STATES PATENT OFFICE

152,273

DESIGN FOR A TRAILER ATTACHMENT FOR
A POWER LAWN MOWER OR THE LIKE

Ralph N. Leonard, Chicago, Ill.

Application January 10, 1948, Serial No. 143,655

Term of patent 7 years

(Cl. D14—3)

To all whom it may concern:

Be it known that I, Ralph N. Leonard, a citizen of the United States, residing at Chicago, in the county of Cook and State of Illinois, have invented a new, original, and ornamental Design for a Trailer Attachment for a Power Lawn Mower or the like, of which the following is a specification, reference being had to the accompanying drawing, forming a part thereof.

In the drawing:

Fig. 1 is a side elevational view of a trailer attachment for a power lawn mower or the like, showing my new design;

Fig. 2 is a top plan view thereof; and

Fig. 3 is a rear elevational view thereof.

The dominant features of the design reside in the portions shown in full lines.

I claim:

The ornamental design for a trailer attachment for a power lawn mower or the like, as shown and described.

RALPH N. LEONARD.
